CLAIM

The ornamental design for a shade structure, as shown and described.

DESCRIPTION

FIG. 1 is a bottom perspective view of a shade structure of the present invention;

FIG. 2 is a front side view of the shade structure of FIG. 1;

FIG. 3 is a right side view of the shade structure of FIG. 1;

FIG. 4 is a left side view of the shade structure of FIG. 1;

FIG. 5 is a rear side view of the shade structure of FIG. 1;

FIG. 6 is a top view of the shade structure of FIG. 1;

FIG. 7 is a bottom view of the shade structure of FIG. 1;

FIG. 8 is a bottom perspective view of a shade structure of the present invention;

FIG. 9 is a front side view of the shade structure of FIG. 8;

FIG. 10 is a right side view of the shade structure of FIG. 8;

FIG. 11 is a left side view of the shade structure of FIG. 8;

FIG. 12 is a rear side view of the shade structure of FIG. 8;

FIG. 13 is a top view of the shade structure of FIG. 8; and,

FIG. 14 is a bottom view of the shade structure of FIG. 8. The broken lines illustrate portions of the shade structure which form no part of the claimed design.
